[57] CLAIM

The ornamental design for a carburetor float bowl adapter for use in oilfield pumping equipment, as shown and described.

DESCRIPTION

FIG. 1 is a front elevational view of a carburetor float bowl adapter for use in oilfield pumping equipment showing my new design, the broken-line showing of engine elements being for illustrative purposes only and forming no part of the claimed design;

FIG. 2 is an enlarged perspective view thereof;

FIG. 3 is an enlarged top plan view thereof;

FIG. 4 is an enlarged left side elevational view thereof;

FIG. 5 is an enlarged bottom plan view thereof;

FIG. 6 is an enlarged right side elevational view thereof;

FIG. 7 is an enlarged rear elevational view thereof, with the knob portion shown omitted.
